UNITED STATES PATENT OFFICE

93,633

DESIGN FOR A FOOD PREPARING DEVICE

Charles W. Rothfeld, Philadelphia, Pa.

Application May 24, 1934, Serial No. 51,911

Term of patent 3½ years

To all whom it may concern:

Be it known that I, CHARLES W. ROTHFELD, a citizen of Austria, residing at Philadelphia, in the county of Philadelphia, in the State of Pennsylvania, have invented a new, original, and ornamental Design for a Food Preparing Device, of which the following is a specification, reference being had to the accompanying drawings, forming a part hereof.

Figure 1 is a plan view of the article, showing my new design.

Figure 2 is a front elevation thereof.

Figure 3 is a side elevation thereof.

Figure 4 is a rear elevation.

This article is adapted to be used for cooking and seasoning a food product commonly known as sausage.

I claim:

The ornamental design for a food preparing device as shown and described.

CHARLES W. ROTHFELD.
